UNITED STATES PATENT OFFICE.

JULIUS AARS DYBLIE, OF CUMMINGS, ILLINOIS.

SHUTTER-WORKER.

SPECIFICATION forming part of Letters Patent No. 310,566, dated January 13, 1885.

Application filed August 26, 1884. (No model.)

To all whom it may concern:

Be it known that I, JULIUS AARS DYBLIE, of Cummings, in the county of Cook and State of Illinois, have invented certain new and useful Improvements in Shutter-Workers; and I do hereby declare the following to be a full, clear, and exact description of the invention, such as will enable others skilled in the art to which it pertains to make and use it, reference being had to the accompanying drawings, which form part of this specification.

My invention relates to an improvement in shutter-workers; and it consists in the combination, with the blind, of a bracket which is secured thereto, a shaft which is pivoted in the window-stole, and which has an arm extending at right angles therefrom, and a connecting-rod which connects said arm with the bracket on the window-blind, as will be more fully set forth hereinafter.

The object of my invention is to provide a mechanical appliance by which I am able to open and shut outside window-blinds from within without raising the window or removing the mosquito-screen.

In the accompanying drawings, Figure 1 is an inside view of my invention as applied. Fig. 2 is a vertical sectional view of the same. Fig. 3 is a top plan view, the blinds and window-frame being shown in section. Fig. 4 is an enlarged detail view.

D represents a shaft which is provided at one of its ends with a square seat corresponding to the square hole in key F, and which has its other end beveled on its upper side, as shown in Fig. 4. This shaft is further provided with an arm, A, which extends at right angles from it near its beveled end. The shaft D is secured in an opening made through the window-stole, and by a double cap, E, secured to the window-sill just behind and in a line with the projection I. This, together with the catch H, secured to the blinds, forms the ordinary lock. Double cap E straddles shaft D on both sides of an arm, A, leaving it free to a circular and reciprocal motion. Pressing shaft D outwardly in its bearings, the above-mentioned bevel on said shaft D will come in contact with the catch H and cause

said catch to rise up and unlock the blind from the projection I. On the shaft D, between the arm A and the outer bearing on the double cap E, is placed a spiral spring, K, the function of which is to keep the shaft D out of contact with the catch H. The opening in the window-stole through which the shaft passes is counterbored from the inside to admit the insertion of the key F, by means of which the shaft is turned.

B represents a bracket which is secured to the inside edge of the blind on or about a level with the catch H, as shown in Figs. 1, 2, and 3. This bracket is connected with arm A by means of a connecting-rod, C.

The operation of my invention is as follows: Supposing the blinds are closed and it is desired to open them, the key is inserted on the shaft, and by pushing it in disengages the catch H. A quarter-turn is then given to the shaft by turning the key F from right to left, or from left to right, according to which blind it is desired to operate. This causes the blind to open, so as to stand at right angles to the wall. Reversing the movement of the key will swing the blind back on the wall, locking itself on its hinges. In closing the blind the operation of the key will be reversed.

Having thus described my invention, I claim—

1. The combination of a shaft having its bearings in the window-frame and provided with an arm, a bracket which is secured to the blind on its inner side, and a connecting-rod connecting the bracket with the arm of the shaft, and means for rotating said shaft, substantially as described.

2. The combination of the shaft D, having a beveled end, double cap E, arm A, secured to said shaft, a spring, K, bracket B, secured to the blind, connecting-rod C, and catch H, substantially as described.

In testimony whereof I affix my signature in presence of two witnesses.

JULIUS AARS DYBLIE.
